SELF-ADJUSTING COSMETIC STICK CONTAINER

Geno M. Ferri, Plymouth, Mass.

Application April 17, 1956, Serial No. 578,746

4 Claims. (Cl. 206—56)

This invention relates generally to cosmetic applicators and is more particularly concerned with a self-adjusting cosmetic stick container.

A primary object of invention is to provide a cosmetic stick container which constantly presents a predetermined length of the cosmetic stick available for use when a removable cover member is removed therefrom.

Another object of invention in conformance with that set forth is to provide in a novel cosmetic stick container of the character involved a protective sleeve member which is movable when the cover member is removed from the container whereby the cosmetic stick is presented in an extended and protected position for use.

And yet another object of invention in conformance with that set forth is to provide in a cosmetic stick container of the character involved means wherby the cover member of the container may be actuated for the purpose of extending the cosmetic stick to a predetermined length for subsequent use.

And yet another object of invention in conformance with that set forth is to provide in a cosmetic stick container of the character involved means whereby the protective sleeve member may be actuated permitting the removal of a used cosmetic stick wherein the same may be replaced by an unused cosmetic stick.

And yet a still further object of invention in conformance with that set forth is to provide a novel cosmetic stick container which is readily and economically manufactured, easily used, and highly satisfactory and acceptable for the purpose intended.

These together with other objects and advantages which will become subsequently apparent reside in the details of construction and operation as more fully herein-after described and claimed, reference being had to the accompanying drawing forming a part hereof, wherein like numerals refer to like parts throughout, and in which:

Figure 1 is an elevational view of the novel cosmetic stick container with a portion broken away and shown in section;

Figure 2 is an enlarged elevational view of the novel cosmetic stick container, with portions broken away and shown in section for clarity;

Figure 3 is a further enlarged vertical sectional view of the novel cosmetic stick container taken substantially on line 3—3 of Figure 2;

Figure 4 is a vertical elevational view of the tubular cosmetic stick carrier member of the novel container;

Figure 5 is an enlarged sectional view taken substantially on line 5—5 of Figure 4; and

Figure 6 is a sectional view taken substantially on line 6—6 of Figure 3.

Referring to the drawing in detail, the novel cosmetic stick container which will be described as being used as a lipstick dispenser, being also usable as a shaving stick or deodorant stick dispenser, for example, is indicated generally at 10, said container including a tubular casing member 12, a base member 14, a tubular cosmetic stick

2

carrier member 16, a cosmetic stock element 18, a protective sleeve member 20 and a removable cover member 22.

As clearly seen in Figure 3, the tubular casing member 12 includes an elongated tubular body portion 24 having a lower crimped edge portion 26 and an upper tapered end portion 28. The body portion 24 of the casing member has extending longitudinally through one side portion thereof an elongated transverse guide slot portion 30, the purpose of which will subsequently become apparent.

The base member 14 includes a bottom portion 32 having extending from one surface thereof an annular flange portion 34 which extends into the lower end of the body portion 24 of the casing member which includes an annular groove thereabout into which the crimped edge 26 is secured. The upper edge portion of the flange 34 indicated at 36 provides a lateral abutment shoulder portion. The bottom portion 32 of the base member includes an outwardly extending peripheral lower flange portion 38 which may terminate in an annular collar portion 40 substantially parallel to portion 34 of said base member and defining therebetween an annular groove 42 extending about portion 34.

The cosmetic stick carrier member 16 includes a tubular body member 44 constructed of a suitable resilient material, said body member 44 terminating at its lower edge in an annular flange portion 46 which may be slidably engageable with the inner periphery of the body portion 24 of the casing member. The body portion 44 has extending through a side wall portion thereof a longitudinally extending upwardly opening elongated notch portion 48 which extends substantially the entire length thereof, see Figure 4, opening into the upper edge 50 of said body portion 44. Extending about an intermediate outer peripheral portion of the body member 44 is a camming flange 52 which is interrupted by the previously mentioned notch portion 48, said flange portion 52 including an inwardly tapered upper edge portion 54 which is engageable with the inner surface of the portion 28 of the body portion 24 of the casing member. A compression spring 56, such as a coil spring shown in Figure 3, is interposed between the flange 46 and the abutment shoulder 36 of the carrier member 16 and base member 14 which is integral with the casing member 12, said spring 56 being effective to urge the casing member outwardly or upwardly as seen in Figure 3, wherein the camming flange 52 will engage the under surface of the portion 28 previously mentioned resulting in inward distortion of the body portion or side walls of the carrier member inasmuch as said carrier member is formed of resilient material. This movement of the side walls of the carrier member will reduce the diameter thereof for the purpose of retaining a cosmetic stick element 18 in a relatively fixed adjusted position within the carrier member 16, this adjustment to subsequently be described in detail.

The cosmetic element 18 comprises a stick of cosmetic material 58 suitably secured in a cap member 60 forming a replaceable cosmetic cartridge. The cosmetic element 18 is reciprocably disposed within the carrier member 16, and a second compression spring 62 is interposed between an inner surface portion of the bottom 32 of the base member 14 and the under-surface portion of the cap member 60. The compression spring 62 is a coil spring which is concentrically disposed within the previously mentioned spring 56, the spring 56 being of a greater strength than the spring 62 and the application of pressure on the bottom of the carrier member 16 results in the distortion of the side walls thereof as previously described wherein the cap member 60 and the cosmetic stick 58 therein will be retained in a relatively fixed position within said carrier member. When the pressure of the spring 56 is relieved, as subsequently will be

described, the compression spring 62 will be effective to urge the cosmetic stick element 18 out of the carrier member 16.

The protective sleeve member 20 includes a tubular body member 64 concentrically disposed on the casing member 12, said body member 64 terminating in an inwardly turned annular flange portion 66 overlying the upper edge 50 of the carrier member, and includes on its lower edge an annular flange portion 68 which is of a sufficient width to be received in the previously mentioned annular groove portion 42 in the bottom portion 14 of the container. The body portion 64 of the protective sleeve member includes an inwardly extending lateral abutment element 70 which is slidingly received in the previously mentioned slot portion 30 in the body portion 24 of the casing member. Downward movement of the protective sleeve member will overcome the compression spring 56 wherein the wall portion of the carrier member 16 will be permitted to assume its normal configuration shown in Figure 4, and when disposed in this position the cosmetic stick element 18 may be removed in toto by virtue of the pressure of the compression spring 62, this procedure being utilized when it is desired to replace a new cosmetic cartridge for one that is no longer usable.

The cover member 22 includes a body portion 72 which is circumscribed about the protective sleeve member 20 the lower edge portion 74 of which being engageable with the flange 68 of the protective sleeve member, said body portion 72 including a closed top portion 76 which overlies the stick of cosmetic stick 58. When the cover member 22 is depressed urging the protective sleeve member 20 downwardly into the previously mentioned annular groove 42 the compression spring 62 will be effective to urge the cosmetic element 18 upwardly into engagement with the undersurface portion of the top of the cover member, and depending upon the distance between the top of the cover member and flange 66 of the protective sleeve member, this will be the length of the cosmetic material available for use. Thus whenever the cover member is disposed on the sleeve member depression of the same will always permit the compression spring 62 to present a given length of cosmetic material to be available for use.

When the cover member 22 is drawn off of the protective sleeve member, the sleeve member will be drawn upwardly therewith as shown by the dotted lines in Figure 3, until the abutment element 70 of the protective sleeve reaches the upper limit of the slot 30 in the casing member, thus, when the cover member 22 is removed the protective sleeve member will surround the usable portion of the cosmetic preventing accidental contact therewith. The protective sleeve member then can be slid or disposed below the cosmetic material 58 and used in a normal manner, and after such use may be again disposed in the dotted line position shown in Figure 3 and the cover member can then be replaced, this latter disposition of the protective sleeve member preventing accidental contact with the cosmetic material.

Thus there has been disclosed a novel cosmetic stick container which fully conforms with the objects of invention heretofore set forth.

Various positional directional terms such as "inner," "outer," etc. utilized herein to have only a relative connotation to aid in describing the device and it is not intended to require any particular orientation with respect to any external elements.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the appended claims.

What is claimed is:

1. A cosmetic stick container for lipstick and the like comprising an elongated tubular casing member, a base member secured transversely on a lower end portion of the casing member, a lateral abutment shoulder portion disposed on the lower inner periphery of the casing member, a flange portion extending from the outer periphery of the base member, the casing member including a tapered upper collar portion, a tubular stick carrier member of a resilient material reciprocably and longitudinally supported in the casing member, a longitudinally extending elongated slot portion extending through a side wall portion of the carrier member and opening into an upper edge portion thereof permitting inward distortion of the side wall portion of the carrier member toward its longitudinal axis, a camming flange portion extending about an outer intermediate peripheral portion of the carrier member for engagement with the tapered collar portion of the casing member, first compression spring means extending between a lower end portion of the carrier member and the abutment shoulder portion of the casing member urging the camming flange portion into engagement with the tapered collar thereof causing distortion of the side wall portions of the carrier member, a cosmetic stick element including a lower cap member reciprocably and longitudinally disposed within the carrier member, inward distortion of the side wall portion of the carrier member retaining the lipstick element in a relatively fixed position, second compression spring means extending between overlying portions of the cap and base members urging the lipstick element toward an extended position, an elongated tubular protective sleeve member reciprocably disposed about the casing member and including an inwardly directed upper collar portion engageable with the upper edge of the carrier member for urging the same toward the base member to permit spring-urged extension of the cosmetic stick from the carrier member, the lower end of the protective sleeve member being disposed in spaced relation from the flange portion of the base member permitting relative longitudinal movement therebetween, guide means extending between the protective sleeve and casing members permitting limited relative longitudinal movement therebetween, an abutment portion extending laterally from the lower outer peripheral portion of the protective sleeve member, and a removable tubular cover member longitudinally disposed on the protective sleeve member and including a lower edge portion engageable with the last mentioned abutment portion for depressing the protective sleeve member to permit extension of the cosmetic element, said cover member including a transverse end portion in spaced relation from the upper end of the protective sleeve member for limiting extension of the cosmetic element, removal of the cover member drawing the sleeve member therewith to the extent permitted by the guide means.
2. A cosmetic stick container for lipstick and the like comprising an elongated tubular casing member, a base member secured transversely on a lower end portion of the casing member, a lateral abutment shoulder portion disposed on the lower inner periphery of the casing member, a flange portion extending from the outer periphery of the base member, the casing member including a tapered upper collar portion, a tubular stick carrier member of a resilient material reciprocably and longitudinally supported in the casing member, a longitudinally extending elongated slot portion extending through a side wall portion of the carrier member and opening into an upper edge portion thereof permitting inward distortion of the side wall portion of the carrier member toward its longitudinal axis, a camming flange portion extending about an outer intermediate peripheral portion of the carrier member for engagement with the tapered collar portion of the casing member, first compression spring means extending between a lower end portion of the carrier member and the abutment shoulder portion of the casing member urging the camming flange portion into engagement with the tapered collar thereof causing distortion of the side wall portions of the carrier member, a cosmetic stick element including a lower cap member reciprocably and longitudinally disposed within the carrier member, inward distortion of the side wall portion of the carrier member retaining the lipstick element in a relatively fixed position, second compression spring means extending between overlying portions of the cap and base members urging the lipstick element toward an extended position, an elongated tubular protective sleeve member reciprocably disposed about the casing member and including an inwardly directed upper collar portion engageable with the upper edge of the carrier member for urging the same toward the base member to permit spring-urged extension of the cosmetic stick from the carrier member, the lower end of the protective sleeve member being disposed in spaced relation from the flange portion of the base member permitting relative longitudinal movement therebetween, guide means extending between the protective sleeve and casing members permitting limited relative longitudinal movement therebetween, an abutment portion extending laterally from the lower outer peripheral portion of the protective sleeve member, and a removable tubular cover member longitudinally disposed on the protective sleeve member and including a lower edge portion engageable with the last mentioned abutment portion for depressing the protective sleeve member to permit extension of the cosmetic element, said cover member including a transverse end portion in spaced relation from the upper end of the protective sleeve member for limiting extension of the cosmetic element, removal of the cover member drawing the sleeve member therewith to the extent permitted by the guide means.

portion of the carrier member and the abutment shoulder portion of the casing member urging the camming flange portion into engagement with the tapered collar thereof causing distortion of the side wall portions of the carrier member, a cosmetic stick element including a lower cap member reciprocably and longitudinally disposed within the carrier member, inward distortion of the side wall portion of the carrier member retaining the lipstick element in a relatively fixed position, second compression spring means extending between overlying portions of the cap and base members urging the lipstick element toward an extended position, an elongated tubular protective sleeve member reciprocably disposed about the casing member and including an inwardly directed upper collar portion engageable with the upper edge of the carrier member for urging the same toward the base member to permit spring-urged extension of the cosmetic stick from the carrier member, the lower end of the protective sleeve member being disposed in spaced relation from the flange portion of the base member permitting relative longitudinal movement therebetween, guide means extending between the protective sleeve and casing members permitting limited relative longitudinal movement therebetween, an abutment portion extending laterally from the lower outer periphery portion of the protective sleeve member, and a removable tubular cover member longitudinally disposed on the protective sleeve member and including a lower edge portion engageable with the last mentioned abutment portion for depressing the protective sleeve member to permit extension of the cosmetic element, said cover member including a transverse end portion in spaced relation from the upper end of the protective sleeve member for limiting extension of the cosmetic element, removal of the cover member drawing the sleeve member therewith to the extent permitted by the guide means, the camming flange including a tapered upper edge portion engageable with an undersurface portion of the tapered collar portion due to the force of the first spring means, engagement therebetween causing the inward distortion of the side wall portion of the carrier member.

3. A cosmetic stick container for lipstick and the like comprising an elongated tubular casing member, a base member secured transversely on a lower end portion of the casing member, a lateral abutment shoulder portion disposed on the lower inner periphery of the casing member, a flange portion extending from the outer periphery of the base member, the casing member including a tapered upper collar portion, a tubular stick carrier member of a resilient material reciprocably and longitudinally supported in the casing member, a longitudinally extending elongated slot portion extending through a side wall portion of the carrier member and opening into an upper edge portion thereof permitting inward distortion of the side wall portion of the carrier member toward its longitudinal axis, a camming flange portion extending about an outer intermediate periphery portion of the carrier member for engagement with the tapered collar portion of the casing member, first compression spring means extending between a lower end portion of the carrier member and the abutment shoulder portion of the casing member urging the camming flange portion into engagement with the tapered collar thereof causing distortion of the side wall portions of the carrier member, a cosmetic stick element including a lower cap member reciprocably and longitudinally disposed within the carrier member, inward distortion of the side wall portion of the carrier member retaining the lipstick element in a relatively fixed position, second compression spring means extending between overlying portions of the cap and base members urging the lipstick element toward an extended position, an elongated tubular protective sleeve member reciprocably disposed about the casing member and including an inwardly directed upper collar portion engageable with the upper edge of the carrier member for urging the same toward the base member to permit spring-urged extension of the cosmetic stick from the carrier member, the lower end of the protective sleeve member being disposed in spaced relation from the flange portion of the base member permitting relative longitudinal movement therebetween, guide means extending between the protective sleeve and casing members permitting limited relative longitudinal movement therebetween, an abutment portion extending laterally from the lower outer periphery portion of the protective sleeve

edge of the carrier member for urging the same toward the base member to permit spring-urged extension of the cosmetic stick from the carrier member, the lower end of the protective sleeve member being disposed in spaced relation from the flange portion of the base member permitting relative longitudinal movement therebetween, guide means extending between the protective sleeve and casing members permitting limited relative longitudinal movement therebetween, an abutment portion extending laterally from the lower outer periphery portion of the protective sleeve member, and a removable tubular cover member longitudinally disposed on the protective sleeve member and including a lower edge portion engageable with the last mentioned abutment portion for depressing the protective sleeve member to permit extension of the cosmetic element, said cover member including a transverse end portion in spaced relation from the upper end of the protective sleeve member for limiting extension of the cosmetic element, removal of the cover member drawing the sleeve member therewith to the extent permitted by the guide means, the camming flange including a tapered upper edge portion engageable with an undersurface portion of the tapered collar portion due to the force of the first spring means engagement therebetween causing the inward distortion of the side wall portion of the carrier member, said casing, carrier, protective sleeve and cover members being concentrically disposed about the longitudinal axis of the cosmetic element, the compression spring means comprising coil springs concentrically related with respect to each other.

4. A cosmetic stick container for lipstick and the like comprising an elongated tubular casing member, a base member secured transversely on a lower end portion of the casing member, a lateral abutment shoulder portion disposed on the lower inner periphery of the casing member, a flange portion extending from the outer periphery of the base member, the casing member including a tapered upper collar portion, a tubular stick carrier member of a resilient material reciprocably and longitudinally supported in the casing member, a longitudinally extending elongated slot portion extending through a side wall portion of the carrier member and opening into an upper edge portion thereof permitting inward distortion of the side wall portion of the carrier member toward its longitudinal axis, a camming flange portion extending about an outer intermediate periphery portion of the carrier member for engagement with the tapered collar portion of the casing member, first compression spring means extending between a lower end portion of the carrier member and the abutment shoulder portion of the casing member urging the camming flange portion into engagement with the tapered collar thereof causing distortion of the side wall portions of the carrier member, a cosmetic stick element including a lower cap member reciprocably and longitudinally disposed within the carrier member, inward distortion of the side wall portion of the carrier member retaining the lipstick element in a relatively fixed position, second compression spring means extending between overlying portions of the cap and base members urging the lipstick element toward an extended position, an elongated tubular protective sleeve member reciprocably disposed about the casing member and including an inwardly directed upper collar portion engageable with the upper edge of the carrier member for urging the same toward the base member to permit spring-urged extension of the cosmetic stick from the carrier member, the lower end of the protective sleeve member being disposed in spaced relation from the flange portion of the base member permitting relative longitudinal movement therebetween, guide means extending between the protective sleeve and casing members permitting limited relative longitudinal movement therebetween, an abutment portion extending laterally from the lower outer periphery portion of the protective sleeve

member, and a removable tubular cover member longitudinally disposed on the protective sleeve member and including a lower edge portion engageable with the last mentioned abutment portion for depressing the protective sleeve member to permit extension of the cosmetic element, said cover member including a transverse end portion in spaced relation from the upper end of the protective sleeve member for limiting extension of the cosmetic element, removal of the cover member drawing the sleeve member therewith to the extent permitted by the guide means, the camming flange including a tapered upper edge portion engageable with an under-surface portion of the tapered collar portion due to the force of the first spring means, engagement therebetween causing the inward distortion of the side wall portion of the carrier member, said casing, carrier, protective sleeve

and cover members being concentrically disposed about the longitudinal axis of the cosmetic element, the compression spring means comprising coil springs concentrically related with respect to each other, the guide means comprising a longitudinally extending slot portion extending into the side wall of the casing member and a lateral abutment element extending from the inner periphery of the protective sleeve member into said slot portion.
